US00D818648S

(12) **United States Design Patent** (10) Patent No.: **US D818,648 S**
(45) Date of Patent: **** May 22, 2018**

(54) **LIP BALM APPLICATORS**

(71) Applicant: **AIROSOLUTIONS NV**,
Heist-Op-Den-Berg (BE)
(72) Inventor: **Mervin Cleij**, Rotterdam (NL)
(73) Assignee: **AIROSOLUTIONS NV**,
Heist-op-den-Berg (BE)
(***) Term: **15 Years**
(21) Appl. No.: **35/501,448**
(22) Filed: **Jul. 27, 2016**

(80) **Hague Agreement Data**

Int. Filing Date: **Jun. 23, 2016**
Int. Reg. No.: **DM/092079**
Int. Reg. Date: **Jul. 27, 2016**
Int. Reg. Pub. Date: **Aug. 26, 2016**

(51) **LOC (11) Cl.** **28-03**
(52) **U.S. Cl.**
USPC **D28/85**
